PRE-PAYMENT DEVICES ADAPTED TO LIMIT THE DURATION OF OPERATION OF A CLOCK-WORK MOVEMENT

Max Weber, Renens, Switzerland, assignor to Etablissement Amora, Vaduz, Liechtenstein

Filed Jan. 31, 1958, Ser. No. 712,421

Claims priority, application Switzerland Feb. 5, 1957

4 Claims. (Cl. 194—19)

Clockwork movements are already known which are combined with a pre-payment device so as not to function until one or more pieces of money have been introduced into an orifice provided for this purpose. These devices are generally known as saving-clocks, which are often loaned by assurance companies for encouraging the public to regularly insert their insurance premium. In known constructions of this type, the mechanism for the introduction of the money is constructed in such a manner that the escapement of the clockwork is braked after a predetermined duration of operation. In some of these constructions, this duration is dependent on the number of coins introduced into the pre-payment device.

This construction has some disadvantages, as firstly the pre-payment device necessitates mechanical parts of considerable precision for acting on the escapement; secondly, the braking action on the escapement is not always very reliable and it influences the accurate operation of the movement in the course of time. Another inconvenience resides in the fact that it is relatively complicated to modify the mechanism for adapting it to another value of pieces of money or another quantity of pieces of money which can be introduced into the device at one time.

The present invention has for its object to remedy these disadvantages. It is directed to a prepayment device adapted to limit the duration of operation of a clockwork movement, comprising an orifice for the introduction of a piece of money and a passage for guiding said latter into a receptacle, a member being located in the path of the coin in such a manner as to be displaced by each coin introduced, characterised in that said member acts on a device recording the number of coins introduced, said device having means for locking the winding mechanism so as to limit the rewinding to a value dependent on the number of pieces of money introduced.

One form of construction of the device forming the subject of the invention is shown diagrammatically and by way of example in the accompanying drawing, wherein:

Fig. 1 is a side view, partly in section, of said device, one of the plates being removed.

Fig. 2 is a section on the line II—II of Fig. 1.

The device shown comprises a winding spindle 1 of which the end 1a (Fig. 2) is adapted to drive the barrel of a clockwork movement, not shown. Said spindle 1 carries a toothed pinion 2 with which it is solid in rotation. Said pinion 2 drives a toothed wheel 3, solid in rotation with a spindle 4 pivoted between two plates 5 and 6. On the spindle 4, a wheel 7 can pivot freely and it is located at the side of the toothed wheel 3. Said latter has a stop 8 adapted to co-operate with a stop 9 of the wheel 7. A spiral spring 10 is secured at its inner end to a part 11 secured to the spindle 4 and at its other end to a pin 12 of the wheel 7.

With reference to Fig. 1, the spring 10 tends to drive the wheel 7 in a clockwise direction in such a manner as to withdraw the stop 9 away from the stop 8. This rota-

2

tion of the wheel 7 is prevented by a lever 13 hinged to a trunnion 14 secured between the plates 5 and 6. One end of said lever 13 projects into a passage 15 adapted to guide the pieces 16 of money which are introduced through an orifice 17. The other end of said lever, in the form of a beak 18, prevents rotation of the wheel 7 by the action which it exerts on screws 19 secured to one face of said wheel. The latter also carries nipples 20 of which the number is equal to that of the screws 19. The end 18 of the lever 13 has a notch 21 adapted to permit the passage of the nipples 20 when the lever is located in the position shown in the drawing.

The winding spindle 1 should be turned in a counterclockwise direction, with reference to Fig. 1 to ensure the necessary rewinding. A mechanism, not shown, prevents the spindle from turning in the opposite direction. It will be seen that in the position shown in the drawing, it is not possible to rewind the clockwork movement, as the movement of rotation which is to be imparted to the spindle 1 should drive the toothed wheel 3 in a clockwise direction, and this rotation is impossible as its stop 8 is in contact with the stop 9 of the wheel 7 which cannot turn in this direction by reason of the action of the end 18 of the lever 13 abutting one of the screws 19. When a piece of money 16 is introduced into the orifice 17, it descends by gravity in its guide passage 15 and during its descent it displaces the end of the lever 13 by causing the latter to pivot against the action of its return spring 22. This movement of the lever 13 disengages its end 18 from the screw 19 and the spring 10 drives the wheel 7 in rotation in a clockwise direction until the nipple 20 abuts against the end 18. After the passage of the piece of money 16, the lever 13 is returned by the spring 22 into its position shown in the drawing and the notch 21 comes into position opposite the nipple 20, whereby the wheel 7 is allowed to turn until the next screw 19 comes into contact with the end of the lever 13. The passage of a piece of money has thus produced a rotation of one-eighth of a revolution of the wheel 7 and the stop 9 has moved away from the stop 8 by a corresponding amount. It is thus possible to turn the winding spindle 1 in a counterclockwise direction until the two said stops again come into contact with one another.

When a number of coins are introduced successively into the orifice 17, the lever 13 is moved a number of times by these coins and at each of its oscillations, the wheel 7 can make a rotation of one-eighth of a revolution. It is possible to rewind the clockwork movement by turning the spindle 1 until the two stops 8 and 9 are again in contact. The amount of rewinding is thus proportional to the number of coins introduced. The wheel 7 can effect at the maximum a rotation less than a complete revolution, during which the stop 9 passes from the left of the stop 8 to the right hand side thereof. When an eighth coin is introduced, the wheel 7 can commence to turn in a clockwise direction under the action of the spring 10 when this eighth coin has caused the lever 13 to rock. Meanwhile, the wheel 7 cannot carry out a rotation equal to one-eighth of a revolution as the stop 9 meets the stop 8 when the lever 13 has resumed its position of rest and a nipple 20 has lightly engaged in the notch 21. This results in a locking of the lever 13, which can no longer rock, even when coins are continued to be introduced into the orifice 17. Said coins thus accumulate upwardly in the passage 15 on the end of the lever 13 and remain blocked in this portion of the passage as long as a rewinding of the clockwork movement has not taken place. When rewinding has taken place, the rotation of the toothed wheel 3 permits of a supplementary rotation of the wheel 7, whereby the lever 13 is released and allows of the passage of the coins accumu-

lated in the passage in proportion to the rewinding. The coins which have actuated the lever 13 then fall into a receptacle, not shown.

When introducing into the orifice 17 coins of which the diameter is smaller than that of the coins for which the pre-payment device is provided, said coins of smaller diameter can pass into the passage 15 without sufficiently moving the end of the lever 13 for releasing one of the screws 19 of the wheel 7.

It is possible to increase the value of rewinding for a definite amount of money by removing some of the screws 19. When removing one of two screws, for example, it will be seen that the wheel 7 can effect, at each passage of a piece of money, a rotation of a quarter of a revolution, which increases the possibility of rewinding. This possibility of adjustment is very advantageous in some cases. Thus, an insurance company may possess a single clockwork model and adjust each clockwork so as to adapt it to the premium which is selected by the insured.

The wheel 7 constitutes, with the lever 13, a device which registers the number of coins passing into the passage 15 and which thus allows of a rewinding proportional to said number of coins. It will be understood that this recording device may be constructed in a different manner and the screws 19 may in particular be replaced by bosses on the wheel 7. The number of these bosses or screws 19, may be of any number desired.

I claim:

1. In a pre-payment device adapted to limit the duration of operation of a clockwork movement, said device having a winding mechanism, an orifice for the introduction of a coin, a passage for guiding said coin into a receptacle, and an oscillating lever located in the path of said coin, so as to be displaced by each coin introduced into said orifice, the combination comprising, means adapted to register the number of coins introduced including a rotatable member engaging with said winding mechanism, said rotatable member comprising a first wheel driven in rotation by said winding mechanism and a movable part for locking said rotatable member and thus locking said winding mechanism, said movable part comprising a second wheel located in side by side relation to said first wheel, each of said wheels having cooperating stop means secured to their opposed faces, said stop means serving to limit the relative rotation of said two wheels, means for driving said second wheel in rotation through

an angle proportional to the number of coins introduced into said orifice to permit the rewinding of said clockwork movement until the said stop means of said first wheel engages the stop means of said second wheel and prevents said first wheel from turning further, thus locking the rewinding of the movement, said oscillating lever acting on said movable part to move it out of its locking position and to allow the rewinding of the clockwork to a value depending on the number of coins introduced in said orifice.

2. A device according to claim 1, wherein the means for driving said second wheel comprises a spring tending to cause it to turn in the same direction as that of said first wheel during the rewinding of said winding mechanism, said oscillating lever cooperating, by one of its ends, with stops carried by said second wheel, so as to prevent it from turning under the action of said spring, the other end of said oscillating lever projecting into said guide passage for the coins in such a manner that each coin produces, during its passage, an oscillation of said lever, in order to liberate the stop from contact with the other end of said lever and thus allowing said second wheel to turn until the next stop comes into contact with said oscillating lever.

3. A device according to claim 2, wherein the stops adapted to co-operate with the end of said oscillating lever are secured to the second wheel in a removable manner, whereby one or more of said stops may be removed so as to vary the value of rewinding for a predetermined amount of money.

4. A device according to claim 1, wherein said second wheel carries two series of stops located respectively on two circumferences, the extremity of said oscillating lever being placed in the path of one of the series of said stops when it is located in one of its extreme positions of oscillation and in the path of said stops of the other series when it is in its other extreme position of oscillation.
